G. J. THOMAS,

TELEPHONE RECEIVER HOLDER.

APPLICATION FILED AUG. 14, 1907.

901,850.

Patented Oct. 20, 1908.

UNITED STATES PATENT OFFICE.

GEORGE J. THOMAS, OF NEW YORK, N. Y.

TELEPHONE-RECEIVER HOLDER.

No. 901,850.

Specification of Letters Patent. Patented Oct. 20, 1908.

Application filed August 14, 1907. Serial No. 888,510.

To all whom it may concern:

Be it known that I, GEORGE J. THOMAS, a subject of the King of England, residing at New York, in the county of New York and State of New York, have invented certain new and useful Improvements in Telephone-Receiver Holders, of which the following is a specification, reference being had therein to the accompanying drawing.

This invention relates to an improvement in telephone-receiver holders, and has for its object the provision of means for facilitating the supporting of a telephone-receiver, thereby permitting a person to carry on a conversation over a wire without employing his hands for supporting the holder.

With this and other objects in view, the invention consists of certain novel constructions, combinations, and arrangements of parts, as will be hereinafter fully described and claimed.

In the drawings: Figure 1 is a view in front elevation of a device constructed in accordance with the present invention. Fig. 2 is a top plan view of the structure depicted in Fig. 1. Fig. 3 is a fragmentary view of the bracket. Fig. 4 is a fragmentary view of the inner end of the arm. Fig. 5 is a perspective view of the detachable bearing and the nut. Fig. 6 is a perspective view of the presser member. Fig. 7 is a fragmentary view of the bracket, showing the clamp device formed on the lower end thereof.

Referring to the drawings, 1 designates the standard of an ordinary desk telephone, which standard constitutes a support. The receiver-rest 2^a is of the ordinary type.

My holder comprises a bracket 2, curved, preferably, at 3, and terminating in a clamp-device 4, formed upon its lower end. The clamp-device comprises a primary member 5 and an auxiliary member 6. The primary member 5 is provided with a curved or semi-cylindrical body 7, and the auxiliary member 6 is also provided with a curved or semi-cylindrical body 8. The primary member 5 terminates at its inner end contiguous to shoulder 9, which shoulder 9 is normally engaged by the inner end of the auxiliary member 6. The primary member 5 is provided with a recess or socket 10 into which projects the lug or pin 11, which lug or pin is integral with the inner face or wall of the auxiliary member 6. A screw 12 is placed in an aperture formed in the auxiliary member 6, and said screw is adapted to

be threaded into a registering aperture 13 formed in the primary member 5. The portions 7 and 8 are placed around the support 1, and by turning the screw 12, the auxiliary member 6 will be securely fastened to the primary member 5, thereby clamping the bracket 2 upon the support 1 or telephone. It is sometimes desirable to place a piece 14 formed of felt, rubber, or any flexible material, around the telephone or support 1 prior to placing the clamp thereon, for preventing the clamp from marring or otherwise injuring the telephone or support.

The upper end of the bracket 3 is bifurcated, thereby producing vertical extensions 15, 15, each of which is provided with a horizontal aperture 16. Extending laterally from bracket 2 is a horizontal, auxiliary bracket 17. Integral with the auxiliary bracket 17 is a vertical, cylindrical body 18, in which is slidably mounted a plunger 19, which plunger 19 is, preferably, provided at its upper and lower ends with suitable heads 20. The lower head 20 normally engages the rest 2^a. A yielding member, preferably, a coil spring 21, is mounted upon the plunger 19, between the upper end of the cylindrical body 18 and the upper head 20. This spring 21 normally exerts an upward pressure upon the upper head 20 and thereby prevents the same from pressing down upon rest 2^a, so that the rest is free to move when pressure is removed from the upper head 20.

The pivotally-mounted arm 22 is provided at its upper end with a clamp similar to the clamp 10 formed upon the lower end of the bracket 2. The clamp upon the arm 22 supports the receiver 23.

The arm 22 is provided with a horizontal, primary portion 24 and with an auxiliary, substantially vertical portion 25. The vertical portion 25 is formed at substantially right-angles to the horizontal portion 24, and said portion 25 is positioned in a vertical plane, while the primary portion 24 is positioned in a horizontal plane, when the telephone is in use. It will, therefore, be noted that the arm comprises a plurality of portions disposed at right-angles to each other, and that by reason of the structure of said arm, the receiver, when in use, is positioned in front and to one side of the mouth piece 26, so that the operator can place his ear against the receiver and his mouth near the mouth-piece and carry on a conversation while his hands are free.

The primary portion 24 of the arm 22 is provided near its inner end with an annular, integral flange or bearing portion 27, which flange or bearing portion is integral with a reduced bearing portion 28. The bearing portion 28 is normally positioned in one of the apertures 16 of the bifurcated portion of the bracket, while the squared portion 29^a is positioned between the bifurcated portions 5 15. The integral screw or threaded member 29 extends through the other aperture of the bifurcated portion of the bracket, and positioned upon this screw, or threaded member 29 is a detachable bearing 30. 10 Threaded upon the extreme outer end of the screw or threaded member 29, is a nut 31, which may be formed in any suitable structure and ornamentally decorated, if desired. 15 The detachable bearing 30 comprises a main or primary portion 32 bearing against the outer face of the bifurcated portion, while the reduced bearing portion 33 is positioned in one of the apertures 16, the same as the reduced bearing portion 28. Horizontal 20 pins or lugs 34 are integral with the inner face of the reduced bearing portion 33, and these pins 34 project into sockets or recesses 35 formed in the squared or polygonal portion 29^a, whereby the detachable bearing, 25 when assembled with the arm, is secured against independent rotary movement with respect to said arm; the same is also true of the presser member 36. The presser member 36 comprises a body portion 37. The 30 body portion 37 is provided with a squared, horizontal aperture 38, through which extends the squared portion 29^a of the integral bearing portion of the arm 22. It will be obvious that by reason of the squared portion 29^a and the squared aperture 38, said 35 presser member is held against independent, rotary movement with respect to the arm 22. Furthermore, this squared structure of the bearing and the aperture constitutes a polygonal structure or key for locking the presser 40 member upon the rotatable arm 22. Extending in opposite directions from the body, and, preferably, formed in parallel planes, 45 are spurs 39 and 40. The spur 39 is adapted to engage the upper head 20 of plunger 19, when portion 25 of arm 22 is placed in a substantially horizontal plane. This position of the portion 25 is assumed when the telephone is not in use. When the telephone is 50 in use, Fig. 1, the spur 40 bears against portion 41 of bracket 2, for limiting the outward pivotal movement of the arm. It will, therefore, be seen that the arm is provided 55 with spurs, one of which actuates the presser member for holding down the rest 2^a, while the other spur limits the pivotal movement of the arm and retains said arm in position for holding the receiver 23 horizontal.

60 While I have shown an ordinary desk

telephone carrying my device, any suitable support may be employed, when it is desired to attach the device to a wall telephone.

What I claim is:

1. A telephone-receiver holder, comprising a bracket provided at its upper end with a bifurcated portion, an arm pivotally mounted upon the bifurcated portion of said bracket, a plunger, means supporting said plunger upon said bracket, a spur carried by said arm within the bifurcated portion of said bracket, said spur adapted to engage said plunger, and telephone-receiver supporting means formed upon said arm. 70

2. In a device of the character described, the combination with a bracket, of a horizontal, auxiliary bracket secured to said bracket, a vertical, hollow portion secured to said auxiliary bracket, a spring-pressed plunger mounted in said vertical, hollow portion, an arm provided with receiver-supporting means, pivotally mounted upon said bracket, and means carried by said arm and capable of being held away from said plunger and adapted to engage and press down upon said plunger. 80

3. A telephone-receiver holder, comprising a bracket, a spring-pressed plunger carried by said bracket, a telephone-receiver holder-arm pivotally mounted upon said bracket, and means carried by said arm and capable of being held away from said plunger and adapted to actuate the same. 90

4. A telephone-receiver holder, comprising a bracket provided with a bifurcated end, a plunger supported upon said bracket, an arm journaled upon the bifurcated end of said bracket, a presser member positioned within the bifurcated end of said bracket and secured against independent rotary movement upon said arm, said presser member comprising a body provided with a squared aperture and said body provided with spurs extending in opposite directions, and receiver-holder carrying means supported by said arm. 100

5. A telephone-receiver holder, comprising a bracket, an arm provided with an integral bearing and an integral, squared portion, journaled upon said bracket, a detachable bearing journaled upon said bracket, means securing said detachable bearing to said arm against independent rotary movement, a spur means securing said spur to the squared portion of said arm, means for actuating a telephone-rest carried by said bracket and adapted to be operated by said spur, and receiver-supporting means carried by said arm. 115

6. A telephone-receiver holder, comprising a bracket, an arm pivotally mounted upon said bracket, said arm provided with a squared portion and with an integral threaded member, a detachable member provided with horizontal pins positioned upon 120

said threaded member, said pins extending into the squared portion of said arm for preventing independent rotary movement of said detachable member with respect to said 5 arm, bodily - movable rest - engaging means carried by said bracket, means carried by the squared portion of said arm and adapted to engage said bodily - movable rest - engaging means, and means for supporting a telephone-receiver upon said arm.

7. A telephone receiver holder, comprising a bracket, an arm extending transversely through and rotatably mounted upon said bracket, vertically-movable means carried to 15 one side of said bracket and supported thereon, and adapted to engage and press down upon a rest, said arm provided with means capable of being entirely removed off of said vertically-movable rest-engaging means and 20 normally adapted to engage said vertically-movable means for pressing down upon a rest, and receiver-supporting means carried by the outer or upper end of said arm.

8. A telephone receiver holder, comprising 25 a bracket, an auxiliary bracket provided with a vertical apertured-portion carried by said bracket, a spring-pressed plunger positioned within the aperture of said auxiliary bracket, an arm journaled in said 30 bracket and extending outwardly therefrom, a member provided with projections or spurs fixedly secured to said arm, one of said spurs adapted to engage said bracket and limit pivotal movement of the arm thereon, and 35 the other spur adapted to engage the plunger for pressing down upon a rest when the device is not in use, and a receiver-holder carrying-means secured to the outer end of said arm.

40 9. A telephone receiver holder, comprising a bracket or support, a rest-engaging mem-

ber slidably mounted upon said bracket, an arm journaled upon said bracket, a presser-member fixedly secured to said arm and adapted to engage said slidale member, 45 said presser member comprising a body provided with a square aperture, and said body provided with spurs extending in opposite directions, and a receiver-holder carrying-means supported by said arm.

10. A telephone receiver holder, comprising a bracket or support, a rest engaging member movably mounted upon said bracket, an arm rotatably mounted upon said bracket, a presser-member secured to said arm and provided with a plurality of spurs or extensions, one of said extensions adapted to hold the arm in an adjusted position, and the other spur adapted to engage and press upon 55 said rest-engaging member when said arm is in an inoperative position, and receiver holder carrying means supported upon said arm.

11. A telephone receiver holder, comprising 60 a bracket, an arm provided with an integral bearing and an integral square portion, journaled upon said bracket, a detachable bearing upon said bracket, means securing said detachable bearing to said square portion, a spur fixedly secured to said square 65 portion, means for actuating a telephone rest carried by said bracket and adapted to be actuated by said spur, and said arm provided with means for supporting an object 70 thereon.

In testimony whereof I hereunto affix my 75 signature in presence of two witnesses.

GEORGE J. THOMAS.
